UNITED STATES PATENT OFFICE.

CHARLES L. HARRISON, OF RICHMOND, VIRGINIA.

VENTILATOR FOR CAR-WINDOWS.

1,150,002.

Specification of Letters Patent. Patented Aug. 10, 1915.

Application filed April 29, 1914, Serial No. 835,147. Renewed July 12, 1915. Serial No. 39,498.

To all whom it may concern:

Be it known that I, CHARLES L. HARRISON, a citizen of the United States, residing at Richmond, in the county of Henrico and State of Virginia, have invented a new and useful Ventilator for Car-Windows, of which the following is a specification.

My invention relates to a ventilating and deflecting screen, especially adapted for use in sleeping car windows, but which is also adapted for general use.

My object is to provide improved novel means for ventilation, novel means for deflecting cinders, rain, etc., and novel and improved means for inserting a device of this kind beneath a raised window and engaging it with the window sash and window frame.

It is also my object to provide novel means for adjusting one of the panel members in my screen so that it may operate more easily.

It is a further object of my invention to provide novel means for securing an adjustable panel in my screen to its raised position for modifying the ventilating effect of the device when desired.

It is my further object to combine the various features of my ventilating and deflecting screen to form the novel device disclosed herein, whereby to provide ventilation and to make the employment of an additional deflector for car windows unnecessary with this device.

I attain these objects by the mechanism illustrated in the accompanying drawings, in which—

Figure 1 is an elevational view of my screen, partly in section, in operative position beneath a window, one of the inner panels being shown in raised position; Fig. 2 is a longitudinal section on line 2—2 of Fig. 1; Fig. 3 is a vertical section on line 3—3 of Fig. 1; Fig. 4 is a vertical section of a modified form of the invention; Fig. 5 is a longitudinal section of one of the casing or screen frames, showing the preferred form of means for securing the lower panel in raised position; Fig. 6 is a detail view of upper corner of the screen frame; Fig. 7 is a detail view of part of the screen frame; and Fig. 8 is a detail view of member Q.

Like letters indicate like parts in the various views.

My ventilating and deflecting screen has two like sections, casings or screen frames, indicated in Figs. 1 and 2 by A and B,

These frames are pivotally connected or hinged as shown in Fig. 2 to permit of the convenient insertion and removal of the device in a portion of a window frame. The pivotal connecting means which I prefer to employ are hinges C, disposed as shown in Fig. 2, mounted on adjacent frame inner members D, with the pivotal portion of the hinge disposed adjacent the outer portion of those members, whereby to permit the insertion of the screen frames in a window casing from the inside of a building or car without having the screen frame project at any time beyond the plane of the window casing. This is a feature of vital importance in the application of my device to car windows, as it can be inserted and removed from within, and without projecting it beyond the car casing where it would be a source of danger.

Each outer frame side member E is provided with a projecting portion F adapted to engage in the window casing to form a rabbed joint (see Figs. 2 and 6), with the objects of securing the screen more firmly in place and also to prevent cinders or water from drifting in.

Each screen frame top member G is provided with a rabbet or recessed portion H, as shown in Figs. 3, 4 and 6, with which the bottom sash of the window may engage, thus forming therewith a rabbed joint when the screen is adjusted in position beneath a window. Members G are provided with an outwardly and downwardly-inclined or deflecting portion I, as shown.

Each screen frame bottom member J is provided with a deflecting outwardly and downwardly-inclined surface K, as indicated in Figs. 3 and 4.

In the outer portion of each screen frame there is provided a reticulated member or screen L, as shown in Figs. 2 and 3. It is within the contemplation of my invention to provide a like reticulated or screen member, adjacent the inner portion of each frame, as indicated in the modified form of my invention illustrated in Fig. 4, or at any other suitable portion of the frame or casing.

I provide novel means for ventilation, comprising a top panel M mounted in the upper portion of each frame, and a bottom panel N mounted in the lower portion of each frame and spaced substantially apart from panel M, which, in the preferred form

of my invention, is substantially as shown in Fig. 3, or in the modified form is substantially as shown in Fig. 4. The ventilating effect is, however somewhat modified by the disposition of panels M' and N' as disposed in Fig. 4, as distinguished from the disposition of panels M and N in the preferred form of my invention illustrated in Fig. 3. As shown in Fig. 3 I employ panels M and N having their unincased or outer edges in approximately the same horizontal plane, or more specifically, in a horizontal plane to or beyond which each of the edges m and n extend. In the modified form shown in Fig. 4 I provide panels M' and N' having edges m and n extending substantially past a horizontal plane that would pass through both panels, diagonally disposed one from the other.

In the preferred forms of my invention, illustrated in Figs. 1, 2, 3 and 5, bottom panel N is slidably mounted in grooves O in side members E and D of each screen frame, as shown. Means for raising and lowering panel N are provided, preferably consisting of a button or handle P. Means for retaining the lower panel N in raised position when desired are provided. Preferably I employ novel springs M mounted in grooves O to frictionally engage and support panel N when raised, as will be understood by referring to Fig. 5; or I provide a suitable arm Q secured to button or handle P, and which may be rotated from horizontal to vertical position to retain panel N in raised position, as shown in Fig. 1 at the right of that figure. Arm Q is preferably of the form shown in detail in Fig. 8 and normally disposed horizontally against panel N, but may be disposed in vertical position at will, to support the panel when so desired.

Means for preventing panel N from sticking and insuring its being freely movable under all conditions may be provided, consisting of rollers R, mounted as shown in Figs. 1, 3 and 7, engaging the sides of the panel.

As already indicated, the screen is operated by opening it outward from a folded position, to engage with a window casing, it being inserted beneath a partially raised window from within a car or building. Projecting tongues F of the outer frame side members E engage with the corresponding grooved portions of the window casings, and the bottom sash of the window engages with the rabbeted or recessed portion H of the screen frame top members G. Reticulated members or screens L (and L' when used) exclude cinders, etc.; and rain, cinders, etc., are deflected by panels M and N also. Deflecting or inclined surfaces K deflect water from the screen frame, and deflecting portion I of top member G performs a similar function.

Ventilation is afforded as the result of substantially spacing apart panels M and N, air from outside being afforded an entrance between the panels, as will be apparent from the drawings. By having the outer or unincased edges of panels M and N terminate in a substantially like horizontal plane a novel construction is presented, which permits free ventilation, with which is combined the function of deflecting cinders, rain, etc., by the deflecting surfaces which the panels provide and which is a more effective means than screening arrangements heretofore in use. The form of my invention illustrated in Fig. 4, presents a novel disposition of panels M' and N' to afford additional or more extensive deflecting surface while at the same time affording ventilation.

Novel means for adjusting the lower panel to a raised position, at the desire of the user is provided and operated as hereinbefore set forth, the panel being slideable to the top of the frame. Novel rollers R engaging the side edges of the panel prevent its becoming wedged against the grooves in which it is mounted, and insures easy operation at all times.

It is within the contemplation of my invention to construct my ventilating and deflecting screen of metal, wood or other suitable materials. Minor changes not involving the novel operation of my screen are also within the contemplation of my invention, and particularly I do not limit myself to a particular size or proportion of parts.

What I claim is:

1. A ventilator adapted to be inserted beneath a window in the sash grooves, comprising a plurality of frame sections each provided with a ventilating orifice, means pivotally connecting the adjacent ends of the sections at the edges exterior to the window when in place, whereby the ventilator may be inserted in the sash grooves without extending the central portion out of the car.

2. A ventilator having the top portion of the frame recessed from the inner edge of said frame member to a line intermediate between its inner and outer edges to afford a recess spaced apart from the outer portion of the ventilator for the reception of the bottom portion of a window sash and having the top portion of the frame beyond the recessed portion thereof disposed on a plane substantially parallel with the recessed portion, adapted to deflect water, etc., and whereby to lock the ventilator in engagement with the window sash.

3. A ventilator having spaced panel members disposed in substantially parallel planes the outer edges of the panel members extending past the same horizontal plane, the upper panel lying in a plane exterior to the inner panel; and means for retaining the

inner panel in raised or open position in the ventilator frame.

4. A ventilator adapted to be inserted beneath a window in the sash grooves, comprising a plurality of pivotally connected frame sections each having laterally projecting tongues formed on the side frame portions adapted to seat in window casing recesses and having the top portion of the frame recessed to allow the bottom portion of a window sash to project into the recess, a portion of the ventilator frame extending upwardly overlapping the bottom of the

window sash, exposed portions of the ventilator frame being outwardly and downwardly inclined, whereby to lock the ventilator in engagement with the window casing and sash and to deflect cinders, water, etc.

In testimony whereof I hereunto affix my signature in the presence of two witnesses.

CHARLES L. HARRISON.
